UNITED STATES PATENT OFFICE.

JONATHAN C. MELOON, OF PROVIDENCE, RHODE ISLAND, ASSIGNOR TO GENERAL FIRE EXTINGUISHER COMPANY, OF NEW YORK, N. Y., A CORPORATION OF NEW YORK.

TAPPING-MACHINE.

1,177,882.

Specification of Letters Patent.

Patented Apr. 4, 1916.

Application filed December 18, 1905. Serial No. 292,275.

To all whom it may concern:

Be it known that I, JONATHAN C. MELOON, of the city and county of Providence and State of Rhode Island, have invented certain new and useful Improvements in Tapping-Machines; and I do hereby declare the following specification, taken in connection with the accompanying drawings, forming a part of the same, to be a full, clear, and 10 exact description thereof.

The object of the present invention is to produce a machine adapted to tap pipe fittings of various kinds, such as T-fittings, elbows, etc., in a more expeditious manner 15 than has heretofore been possible, and by means of which the number of fittings which may be tapped in a given time may be greatly increased as compared with the work done by machines heretofore in use.

To that end the invention consists primarily in the combination of a series of tapping mechanisms, a main driving shaft for operating all of said tapping mechanisms, and independent connecting mechanism between said driving shaft and each of said 25 tapping mechanisms whereby each set of taps may be operated independent of the other set or sets.

A further feature of invention consists 30 in providing each of said independent connecting mechanisms with means for reversing the direction of rotation of the tapping mechanism or devices, whereby each set of taps may be reversed independent of the 35 other set or sets.

A further feature of invention consists in providing each of said independent connecting mechanisms with means for changing the speed of the tapping mechanism, 40 whereby the speed of each set of taps may be changed independent of the other set or sets.

A further feature of invention consists in providing each of said independent connecting mechanisms with means whereby the direction of rotation of the tapping mechanism may be automatically reversed, and also if desired with means whereby the rotation of said tapping mechanism may be 45 automatically stopped.

The invention also comprises certain features of construction which will be herein-after described and claimed.

Referring to the drawings, Figure 1 is a

front view of the machine; Fig. 2 is a central vertical section; Fig. 3 is a horizontal section through one of the tapping mechanisms of the machine.

The machine shown in the drawings comprises three tapping mechanisms arranged one above the other, each tapping mechanism embodying three taps adapted to tap simultaneously the three openings of a T-fitting. Preferably each tapping mechanism is mounted in a separate frame, the three frames A^1 A^2 A^3 being bolted together, as shown, and the lower frame A^1 being bolted to the supporting frame or standard A. The three tapping mechanisms are operated, preferably by chain drives, from a single main driving shaft 1 mounted in the standard A. A second shaft 2 is mounted in said standard parallel with the shaft 1 to which it is geared by the gears 3, 3, and so that said shaft 2 will be rotated in a direction reverse to that of shaft 1. The main driving shaft 1 may be driven in any desired manner, being shown as provided with a driving pulley 4 actuated by the belt 5.

The shaft 1 is provided with three sprocket wheels 6, for actuating the driving chains 7, one for driving each of the three tapping mechanisms, and the shaft 2 is provided with three sprocket wheels 8 for driving the chains 9, each of which is likewise connected with one of the tapping mechanisms.

Except for the necessarily different location of the sprocket wheels, resulting from the arrangement of the driving chains, each of the tapping mechanisms is a duplicate of the other, and a description of one of said tapping mechanisms will therefore be sufficient.

Referring to Fig. 3, 10 is a shaft mounted in the frame, upon which shaft are loosely mounted the two sprocket wheels 11 and 12, the sprocket wheel 11 being driven by one of the chains 7 and the sprocket wheel 12 being driven by one of the chains 9. When the sprocket wheel 11 is connected to the shaft, said shaft will be rotated in one direction, and when the sprocket wheel 12 is connected to the shaft said shaft will be rotated in the opposite direction.

Any desired form of shifting clutch mechanism may be employed for alternately con-

necting said sprocket wheels with the shaft. In the drawings a common form of friction clutch mechanism is shown, comprising two clutch members 13, 13^a, one connected to each of the sprocket wheels, and mounted on the shaft between these two clutch members is a shifting clutch member 14, said shifting clutch member being connected to the shaft 10 by a groove and spline connection, so as to be rotated with the shaft, but so as to be capable of lengthwise movement thereon. A second shaft 15 is mounted in the frame of the section parallel with the shaft 10, the two shafts being connected by change gears 16, which change gears may be removed and other gears substituted to change the speed of the shaft 15. Each tapping mechanism embodies three tap-spindles, two of which, 17 and 18, are arranged in line with each other, the third spindle 19 being at right angles to the other two, as shown in Fig. 3.

The three spindles are all driven from the shaft 15 in the following manner: Secured to said shaft 15 is a worm 20 which meshes with a worm wheel 21 on the spindle 19. Also secured to said shaft are two bevel gears 22, 23, the bevel gear 22 meshing with a corresponding bevel gear 24 on the shaft 30, on which said shaft is a worm 26 which meshes with a worm wheel 27 on the spindle 17. The bevel gear 23 meshes with a corresponding bevel gear 28 on the shaft 29 and on this shaft is mounted a worm 30 which engages the worm wheel 30^a on the spindle 18. Preferably each of the worm wheels is located in a pocket, as shown in the drawings, which pocket forms a receptacle for oil in which the worm and worm wheel run. By this construction all three of the spindles are simultaneously driven and at the same speed.

Keyed on the outer end of each spindle is a removable threaded sleeve 31 which constitutes a lead screw for the spindle. The inner end of said sleeve 31 abuts against a shoulder formed on the spindle, and said sleeve is held in place on the spindle by a nut 32 screwed on to the threaded end of the spindle as shown. The purpose of employing this removable sleeve is to permit the substitution of different sleeves having different pitches of screw-threads to provide different leads for the spindle according to the tap to be operated. The worm wheel on each spindle is keyed on the spindle so as to permit the advancement and retraction of the spindle in the operation of the tap. Each of the spindles 17 and 18 is also provided with means whereby the spindle may be adjusted toward or from the work.

Surrounding the removable sleeve 31 is an adjusting sleeve or nut 33 which is internally screw-threaded on its inner end to engage the screw threads on the sleeve 31,

and is also exteriorly screw-threaded but with a different pitch to engage a corresponding thread formed in the boss 34 on the frame. Said adjusting sleeve 33 may be provided with one or more projecting handles for turning the same. Mounted on said sleeve is a lock-nut 35 for locking the adjusting sleeve in any adjusted position, said lock-nut being likewise preferably provided with handles for turning the same. A corresponding adjustment of the spindle 19 is not necessary, because this spindle may be brought up to the proper position in the first instance and then the other two spindles adjusted with relation to it. In the case of said spindle 19 the nut 33 is provided with a flange which is brought up into engagement with the boss on the frame and does not require to be afterward disturbed.

Referring next to the mechanism for shifting the shifting clutch to reverse the direction of rotation of the spindles, two means are shown in the drawings for shifting said clutch, one means for shifting said clutch by hand and the other for shifting said clutch automatically, the automatic means shown being adapted to be operated by compressed air.

Mounted in suitable bearings in the frame is a rock shaft 36 which is provided at its forward end with an operating handle 37. Near the rear end of said shaft is a projecting arm 38 provided with a fork 39 which engages a groove in the shifting clutch member 14. By moving the operating handle in one direction or the other the shaft 36 is rocked and the shifting clutch member thereby shifted. The operating handle is so arranged on the rock-shaft that when said handle stands in a vertical position, as shown in the upper section in Fig. 1, the clutch member will be in mid-position and disengaged from both of the sprocket wheels. When said operating handle is moved to the right and into the position shown in the second section in said figure, the shifting clutch will be engaged with the clutch member secured to the sprocket wheel 12, and when the operating handle is moved in the opposite direction and into the position shown in the third section in Fig. 1, the shifting clutch member will be moved into engagement with the clutch member secured to the sprocket wheel 11.

The arrangement for automatically shifting the clutch member 14 is as follows: Secured to a suitable bracket 40 mounted on the frame is a cylinder 41 containing a piston adapted to be operated by compressed air, said piston being provided with a piston-rod 42. Mounted in a bracket 43 also secured to the frame is another rod 44 in line with the piston rod. This rod 44 is turned down to provide two annular shoulders 45, 46, separated from each other at the proper dis-

tance. The outer end of the piston-rod 42 is screw-threaded and is screwed into the end of the rod 44, the parts being locked in position by a lock-nut. Projecting upward from the rear end of the rock shaft 36 is an arm 5 provided with a fork 47 at its upper end which straddles the rod 44 between the two annular shoulders 45, 46. The cylinder 41 is provided with suitable valves controlling the ports for the admission and exhaust of the compressed air from said cylinder, and these valves are adapted to be operated by means of a swinging lever 48 pivoted to the cylinder at one end and with its free end located between and in line with the projecting valve stems 49, 50, said valve stems being connected with the controlling valves. On the outer screw-threaded end of the spindle 19 are located two nuts 51, 52, which nuts 20 are adapted, as the spindle is caused to travel in one direction or the other, to strike the pivoted lever 48 and swing said lever first in one direction and then in the other, the position of said nuts on the spindle being 25 adjusted so as to swing said lever and thus automatically shift the clutch-member 14 at the proper times. Thus, supposing the spindles to be advancing, as the spindle 19 approaches the limit of its inward movement 30 the nut 51 will strike the pivoted lever 48 and throw it over so as to push in the valve-stem 50 and open the controlling valve connected therewith, whereby the piston will be actuated in a direction to shift the clutch 35 member 14 out of engagement with the clutch member 13 and into engagement with the clutch-member 13^a, thereby causing the spindles to be rotated in the opposite direction and in a direction to retract the same.

40 If desired, when the spindles have been retracted they may be again automatically reversed and caused to advance.

In order to give time for the operator to remove one fitting and put in another, it is 45 preferred to stop the spindles after they have been retracted, and in the arrangement shown in the drawings this is done automatically, the stopping of the spindles being provided for by the lost motion furnished 50 by the space between the two annular shoulders 45, 46, engaged by the fork 47 on the rear end of the rock shaft 36. Thus, as shown in Fig. 3, in which the parts are represented in the position which they occupy 55 after the piston has been operated by the retracting movement of the spindle, it will be seen that the fork 47 on the rock shaft has been moved only to a vertical position, and so as to bring the shifting clutch member 60 into mid-position and out of engagement with both of the sprocket wheels. When the operator has removed the fitting and put in another, he starts up the tapping mechanism by hand by throwing the operating handle of 65 the rock shaft in the proper direction to en-

gage the clutch member 14 with the clutch member 13.

The piping for conducting the compressed air to the cylinder 41 is shown in Fig. 2 and need not be described in detail.

Referring next to the means for holding the fitting while it is being tapped, such means comprises two jaws, one fixed and the other movable, arranged to clamp the fitting on opposite sides. The stationary jaw 53 in 70 the form shown in the drawings is provided with a short downward circular projection 54 constructed to fit a corresponding hole or socket in the frame, by means of which projection the lower jaw is properly located 75 with relation to the spindle. A dowel pin 55 is provided to prevent the lower jaw from turning in its socket. The movable jaw 56 is secured to a bar 57 adapted to slide in 80 guide-ways 58, and so that the movable jaw 85 may be moved to a position over the fitting or be moved away from the fitting to permit the removal thereof. The rear end of this sliding bar is provided with a stop 59 arranged to engage the frame or some other 90 suitable abutment, whereby the forward movement of the movable jaw is limited, said stop being so located that when said stop abuts against the frame the movable 95 jaw will have been brought to the proper position above the fitting. The guide-ways 58 serve to properly guide the bar 57 and the movable jaw 56 as the jaw is moved from one position to the other.

When the movable jaw has been brought 100 to the proper position above the fitting it is forced against the fitting to clamp the same by an adjusting screw 60 which takes into a nut 61; said screw being provided with a hand wheel 62 for turning the same. 105 Means are provided for adjusting the position of this clamp screw so that it may be brought into different positions as may be required with the different styles or kinds of fittings to be tapped and the form of movable jaw suitable therefor. For the purpose of adjusting the position of said clamp screw the nut 61 is adjustably secured to the frame by means of a clamp bolt 63 passing through an elongated slot 64 in a flange projecting from said nut. The flange on the opposite side of the nut is engaged by the head of a hook bolt 65 which may be turned to release the nut and permit it to be changed 110 in position. Thus the nut and screw may be moved bodily laterally within the range of the slot in the flange, and may also be turned about the clamp bolt 63 as a center. By this means the clamp screw for the movable jaw may be brought to any desired position. 115 As will be understood, each pair of jaws, the fixed jaw and the movable jaw, is made of the proper form and size for a given fitting, and the jaws are changed when 120 a different sized fitting is to be tapped. 125

The operation of the mechanism above described will be readily understood. Assuming the machine to be provided with a series of three tapping mechanisms, as shown in the drawings, and assuming that the spindles of each tapping mechanism are in their retracted position and the clamping jaws released and the upper jaw moved backward, as shown in the lowermost section in Fig. 1, the operator places the fitting, which may be assumed to be a T-fitting, in position on the lower jaw, then pulls the upper jaw forward in proper position above the fitting, and by turning the hand-wheel 62 forces the clamp-screw 61 downward and so as to securely clamp the fitting between the two jaws. The operator then throws the operating handle 37 from its upright or mid-position to the left, thereby throwing the shifting clutch member 14 into engagement with the clutch member 13 and so that the shaft 10 will be rotated in the proper direction to advance the spindles to cause the taps to engage and act upon the fitting. When this has been done the operator next places a fitting in position to be operated upon by one of the other tapping mechanisms, clamps it in position, and starts up the tapping mechanism, and thereafter proceeds in the same manner with the third tapping mechanism. By the time he has started up the third tapping mechanism the fitting first placed in position will have been tapped and be ready to be removed from the machine, the tap spindles continuing to advance until the nut 51 on the spindle 19 engages the swinging lever 48, thereby causing the direction of rotation of the spindles to be reversed and the spindles retracted until the taps have cleared the fitting, when the nut 52 will swing the pivoted lever in the opposite direction, thereby causing the shifting clutch member 14 to be moved into mid-position and the tapping mechanism to be stopped. The operator then removes the finished fitting and places another in position. Thus with a series of three tapping mechanisms in the machine, one set of taps may be advancing to do their work, another set may be at the same time retracting, while the third set may be at rest while the operator is placing a fitting in position, or as the spindles may be retracted at a greater speed than they are advanced, the machine may be so organized that two sets of taps may be advancing at the same time, one set of taps completing its advancing movement while the next set of taps is commencing to advance. In either case the tapping mechanisms are organized so as to break joints, as it were, and thus prevent practically any lost time, one set of taps being practically always operating upon a fitting. If desired the number of tapping mechanisms may be either less than three or more than three,

but I find the employment of three tapping mechanisms to be preferable, as thereby the fittings are tapped as rapidly as one operator can remove the finished fittings and place the blanks in position.

As will be seen, all of the tapping mechanisms are operated from a single driving shaft, but the connecting mechanisms which connect the driving shaft with the several tapping mechanisms, are each independent of the other, and thus each set of taps is operated independent of the other set or sets. It will also be seen that each tapping mechanism may be reversed independent of the others and so that each tapping mechanism may be reversed at the desired time and without reference to whether the spindles of the other tapping mechanisms are advancing or retracting or are at rest. It will be further seen that by changing the change gears of one tapping mechanism such tapping mechanism may be operated at a different speed from the others and so that one tapping mechanism may be operating upon a fitting of one size and requiring a certain speed for the taps, while the other tapping mechanisms may be operating upon fittings of another size and requiring a different speed for the taps.

While I have shown change gears as the means for changing the speeds of the tapping mechanisms, it will be understood that any other form of speed changing mechanism may be employed for the purpose.

It will be noted that in the machine shown in the drawings the spindles of each tapping mechanism will be advanced to tap the fitting, and when the operation has been completed the spindles will be automatically retracted and when retracted the operation of the spindles will be automatically stopped to permit the removal of the fitting and the insertion of another, leaving nothing for the operator to do but to start up the tapping mechanism when the next fitting has been clamped in place. While this construction and arrangement are preferred, the starting, reversing and stopping of the spindles may, if desired, be performed by hand, so far as the main features of the invention are concerned, and so also if desired the spindles might be automatically advanced immediately upon the completion of their retracting movement, if sufficient time were provided in some way for the operator to remove the finished fitting and replace it with another.

While the means shown for automatically reversing and stopping the spindles are constructed to be operated by compressed air, any other suitable means may be employed for thus automatically controlling the movements of the spindles.

It is preferred to locate the several tapping mechanisms one above the other as

shown, as this affords the most convenient arrangement for the operator and enables him to place and remove fittings in each of the tapping mechanisms without changing his position, but if desired the several tapping mechanisms may be otherwise arranged.

What I claim as my invention and desire to secure by Letters Patent is:

- 10 1. A tapping machine having in combination a series of tap-spindles, means for advancing and retracting said spindles, means actuated by the advancing movement of one of said spindles for automatically reversing said spindles when they have completed their advancing movement and means for automatically stopping said spindles when they have completed their retracting movement.
- 15 2. A tapping machine having in combination a series of tap-spindles, means for reversing the direction of rotation of said spindles, a piston for operating said reversing means, valves for controlling the movements of said piston, and means actu-
- 20
- 25

ated by one of the spindles for operating said valves.

3. The combination with a tap-spindle provided with a lead-screw, of a nut for said lead-screw, said nut being screw-threaded in the frame, means for turning said nut, and a lock-nut for locking said lead-screw nut, whereby said lead-screw nut also serves as an adjusting nut for adjusting the position of the tap-spindle.

30 4. The combination with a tap-spindle, of a removable screw-threaded sleeve mounted on said spindle, the thread on said sleeve constituting the lead-screw for said spindle, and an adjusting nut, said nut being provided with an interior screw-thread to 35 engage said lead-screw and with an exterior screw-thread of different pitch to engage the frame, whereby said nut acts both as a nut for the lead-screw and as an adjusting nut to adjust the position of the spindle.
